UNITED STATES PATENT OFFICE

171,575

PORTABLE SHOWER

Charles J. Bergh, Jr., Havertown, Pa.

Application March 31, 1953, Serial No. 24,275

Term of patent 3½ years

(Cl. D91--3)

To all whom it may concern:

Be it known that I, Charles J. Bergh, Jr., a resident of Havertown, Delaware County, Pennsylvania, have invented a new, original, and ornamental Design for a Portable Shower, of which the following is a specification, reference being had to the accompanying drawing, forming a part hereof.

Fig. 1 is a perspective view of a portable shower showing my new design;

Fig. 2 is a top plan of the same;

Fig. 3 is a front elevation of the same;

Fig. 4 is a rear elevation of the same.

I claim:

The ornamental design for a portable shower, as shown.

CHARLES J. BERGH, JR.
